UNITED STATES PATENT OFFICE.

CLINTON F. SHADLE, OF CLEVELAND, OHIO, ASSIGNOR, BY MESNE ASSIGNMENTS, TO
B. A. WORTHINGTON, TRUSTEE, OF NEW YORK, N. Y.

SIGNAL SYSTEM FOR RAILWAYS.

1,259,789.

Specification of Letters Patent. Patented Mar. 19, 1918.

Application filed April 23, 1915. Serial No. 24,751.

To all whom it may concern:

Be it known that I, CLINTON F. SHADLE, a citizen of the United States, residing at Cleveland, in the county of Cuyahoga and 5 State of Ohio, have invented certain new and useful Improvements in Signal Systems for Railways, of which the following is a specification.

It is the object of my invention to provide an improved signaling system for railways employing a traveling signal device which operates in accord with the electric condition of the track circuit controlling a local signal device in advance of the location of the traveling signal device. It is a further object of my invention to provide an improved signaling system for railways wherein the track is divided into blocks of suitable lengths, and embodying local control stations for the blocks controlled by normally closed circuits extending lengthwise of the tracks, and a traveling control device controlled in accord with the circuit of a block in advance of the block in which 25 the traveling control device is located, and further to provide local contact-means in the block occupied by the traveling control device having circuit connection with the control-station of said block in advance.

30 It is a further object of my invention to provide traveling signaling mechanism embodying traveling electric connections and a traveling electric translating device which is controlled by the flow of electricity in track circuits of advance blocks; further to provide such translating device as an electric pole-changer; further to cause selective operation of selective traveling signal or train-control devices in accord with 35 the presence or absence of closed circuit condition of the track circuit of an advance block or the direction of flow through said closed track circuit, for indicating, for instance, a clear block, a caution block, or a danger block ahead, and in case of a danger block desirably causing actuation of a train control mechanism for causing stoppage of the train, such train control mechanism desirably causing actuation in the usual braking system of the train.

It is the object of my invention further

to provide local signal stations comprising signals controlled by said flow of electricity in said track circuits of advance blocks, and electric connections controlled thereby comprising local contacts for said traveling electric connections for setting up said traveling electric translating device in accord with said track circuit of said advance block; further to provide a traveling main- 55 taining circuit for maintaining said traveling electric translating device in set-up relation; and further to provide a traveling normally interrupted circuit arranged to reset up said traveling electric translating de- 60 vice after interruption in the same due to danger condition thereof.

It is the object of my invention further to provide a local battery, a local contact, and electric connection therebetween em- 70 bodying a pole-changer, a traveling battery, a traveling contact for said local contact, and electric connection therebetween em- bodying a pole-changer, and a traveling po- 75 larized magnet arranged to be placed in cir- circuit with each of said batteries, further to so arrange the parts that said polarized magnet is momentarily placed in circuit with both said batteries, and further to pro- 80 vide electric resistance in said electric con- nections of said traveling battery whereby the current of said local battery is caused to follow a course to the relay during said momentary placing of said polarized mag- 85 net in circuit with both said batteries; fur- ther to provide traveling electrically con- trolled signal devices the electrical connec- 90 tions whereof embody a pole-changer con- trolled by said traveling polarized magnet for selectively operating said traveling sig- 95 nal devices; and further to so arrange said traveling signal devices and electric connec- tions as to operate in accord with corre- 100 sponding local signal devices controlled by advance blocks.

It is the object of my invention further to employ the present established and approved track circuit and local signaling and local signal operating means now in general use upon railways, and to superpose thereon traveling signaling and controlling means without interference with the track and local

signaling and local signal operating means or causing interference in the electric circuits thereof, and to provide means whereby the signals on the traveling vehicle appear as duplications of the local signals of advance blocks, so that the driver, whether he be engineer, motorman or other operator of the traveling vehicle, may be advised in advance of arriving at such advance block, 10 of the condition of said advance block, and, desirably so that the vehicle may be automatically stopped prior to reaching the danger block.

The invention will be further readily understood from the following description and claims, and from the drawings, in which latter:

Figure 1 is a diagrammatic representation of an exemplification of my invention. 20 Fig. 2 is a diagrammatic representation of the traveling portions of said exemplification.

Fig. 3 is a side elevation of one of the traveling contact mechanisms.

25 Fig. 4 is a front elevation of the same.

Fig. 5 is a vertical section of the same taken on the line 5—5 of Fig. 4, and showing the traveling contact in flexed relation, the rail being shown in side elevation.

30 11 and 12 represent the respective rails of a track which is divided into blocks of suitable lengths and suitable number, four of these blocks being indicated at A, B, C and D, separated by insulations 13.

35 B', C' and D' represent local stations at the entrance to the blocks B, C and D respectively. The parts at the respective local stations have corresponding reference letters and numerals applied thereto.

40 In the present exemplification the rail 11 is represented as the normally positive electric conducting rail of the system, and the rail 12 as the normally negative conducting rail of the system.

45 At each local station there is preferably a local signal 16, shown as a semaphore-arm, to indicate the condition of the block, at the entrance to which the signal is located. In the present exemplification the 50 semaphore-arm at station B' is in normal or upright position, its spectacle 17 showing white, to indicate a clear or proceed condition of block B, the semaphore-arm at station C' is in slanting position, its spectacle 18 showing green, to indicate a caution condition of the block C, and the semaphore-arm at station D' is in horizontal position, its spectacle 19 showing red, to indicate a danger condition of block D.

55 60 In the present exemplification the signal is operated by compressed fluid, although it is within the scope of my invention to employ other means for operating the same. The compressed fluid is shown controlled by 65 electrically operated valves.

21 represents a local signal control battery, which controls the electro-pneumatic valves 23, 24, communicating by passages 25, 26, with cylinders 27, 28, in which pistons 29, 30, operate. A piston-rod 31 extends from the piston 29 into the cylinder 28, and a piston-rod 32 is articulated with a lever 33 pivoted by a pivot 34 in the base of a suitable signal-mast, and articulated at 36 with an actuating rod 37 extending 70 lengthwise of the signal-mast and articulated at 38 to the semaphore-arm, the latter being pivoted on a pivot 39 to the signal-mast.

75 A pipe 41 leads from a suitable source of compressed air to the inlet-port of the electro-pneumatic valve 23, and a pipe 42 leads from the passage 25 to the inlet-port of electro-pneumatic valve 24, these inlet-ports being designated by the reference letter *a*. 80 Each of the electro-pneumatic valves has an inlet-valve *b* and an outlet-valve *c*, the latter communicating with an outlet-port *d* opening to the atmosphere. The valves *b* and *c* are connected by a stem *e* and are actuated 90 by an electric translating device represented as an electro-magnet, these electro-magnets being designated 43 and 44 respectively. The electro-magnets normally cause opening of the inlet-valves and closing of the 95 outlet-valves, as shown at station B', for depressing the pistons and moving the signal into white or clear position.

100 When the compressed fluid is shut off from cylinder 28 and said cylinder is opened by the breaking of the circuit of magnet 44, the weight of the semaphore-arm causes retraction of the piston 30 until it strikes the piston-rod 31, which is held by the pressure on its piston, bringing the signal to green 105 or caution position shown in station C'. When the circuit of electro-magnet 43 is broken, compressed fluid will also be shut off from cylinder 27 and said cylinder opened to the atmosphere, allowing retraction of both pistons and causing the semaphore-arm to descend by gravity to red or 110 danger position, as shown at station D'.

115 The armatures of electro-magnets 43, 44, are actuated through the medium of the signal-control battery 21. Electric conductors 46, 47, having a circuit interrupter 48 therein, connect one of the poles of the battery 21 with one of the terminals of the electro-magnet 43 and an electric conductor 49 connects the other pole of the battery 21 with the other terminal of the magnet 43. Electric conductors 46, 53, having a circuit-interrupter 54 therein, connect one of the poles of the battery 21 with one of the terminals of the electro-magnet 44, and electric conductors 49, 55, connect the other pole of said battery with the other terminal of said magnet 44.

120 The circuit-interrupters 48, 54, are con- 130

trolled from an advance local station, preferably from the station at the entrance to the next block in advance. Thus the said circuit-interrupters at station B' are controlled from the local station C' through the medium of a track circuit.

61 represents a track battery. A pole-changer 62 is interposed between said battery and the track. The pole-changer is represented as having contact-arms 63, 64, connected by an insulated bar 65, and arranged to coöperate with contacts 66, 67, 68. One of the arms is articulated at 69 with the signal-rod 37. The contacts 66, 68, are connected by electric conductors 70 with the negative pole of the track battery, while the contact 67 is connected by an electric conductor 71 with the positive pole of the track battery. An electric conductor 72 connects the arm 63 with the rail 11 of the block in rear of the one at the entrance to which the local signal is located, and an electric conductor 73 connects the arm 64 with the rail 12 of said block.

25 The circuit-interrupters 48, 54, of the local station at the entrance of the block with which the electric conductors 72, 73, connect, are controlled by a local-translating device 74, shown as a relay, energized by the track battery of said block. An electric conductor 75 connects the rail 11 of said block with one of the terminals of said relay and an electric conductor 76 connects the rail 12 of said block with the other terminal of said relay. Said relay is preferably a polarized relay comprising a polarized armature forming the circuit-interrupter 54, and a neutral armature forming the circuit-interrupter 48.

40 When now the local signal is in white or clear position, as shown at local station B', which is the local station for the block in advance B, the pole-changer 62 will be in such position that the positive pole of the track-battery at said local station will have connection with the right-hand or normally positive rail of the block in rear A, and the negative pole of the track-battery will have connection with the left-hand or normally negative rail of said block in rear A, for energizing the polarized relay at the entrance of said block and causing a current therethrough in accordance with the position of the pole-changer 62 at local station B', and closing the circuit-interrupter in the electro-pneumatic valve circuits at the entrance of said block A in the absence of a vehicle or other obstruction in said block.

60 The presence of a vehicle in said block A, indicated at W, will however short circuit the track-battery across said rails through the wheels and axles of the vehicle and take the current from said polarized relay and thereby open said circuit interrupter 48, 65 which is a neutral armature, causing the

signal at the entrance to block A to go to red or danger, a relation shown at local station D', the circuit interrupter 54 having been previously swung for green or caution condition of block.

This relation changes the poles in the pole-changer 62 at local station D', so as to connect the right-hand rail of block C looking in the proceed direction, with the negative pole of the track-battery 61 at station D', thereby reversing the polarity of the polarized relay 74 at station C' and causing a swinging of the circuit interrupter 54, which is a polarized armature, so as to break the circuit energizing the coil of electro-pneumatic valve 24 at said station C' and causing the signal at said station C' to move to green or caution position.

Electric connections are further made with the local signal control battery 21 and continued into a different block, for instance, a block in rear, where local contacts for the same are provided, forming a normally interrupted or partial circuit. These electric connections comprise pole-changing mechanism for causing the polarity of said local contacts to correspond to the polarity of the rails of the block served by said local signal control battery, traveling signal mechanism being provided which coöperates with said local contacts for duplicating in said traveling signal mechanism the signal caused by the control of said local signal control battery or electric translating device. This pole-changing mechanism is shown as a mechanical pole changer but my invention includes any character of circuit continuing or duplicating mechanism.

81 represents a pole-changer embodying contact-arms 82, 83, connected by an insulated bar 84, the arm 83 being articulated at 85 with the signal actuating rod 37. Contacts 86, 87, have electric connection with the negative pole of the local signal control battery 21, as by means of an electric conductor 50, which has a circuit-breaker 51 therein. A contact 88 has electric connection with the positive pole of the local signal control battery 21, as by being connected with the electric conductor 46. The circuit-breaker 51 is pivoted at 56 in the base of the signal-mast and articulated at 57 with the signal operating rod 37. An electric conductor 89 connects with the contact-arm 82 and extends lengthwise of the track a suitable distance and connects with a local contact 90. An electric conductor 91 connects with the contact-arm 83 and extends lengthwise of the track a suitable distance and connects with a local contact 92.

These local contacts are preferably local contact-rails insulated from the trackage and traffic rails, and may be short rails of say six to eighteen feet in length placed opposite each other at opposite sides of the

track at a suitable distance from the block at the entrance to which the local signal station from which their electric conductors extend is located, this distance determining 5 the length of time of travel throughout which the driver of the oncoming vehicle will have advance information of the state of the signal at the local signal station which he is approaching.

10 The right-hand local contact looking in the proceed direction is normally the positive local contact, corresponding to the normal polarity of the proximate rail, and the left-hand local contact is normally the negative local contact, corresponding to the normal polarity of the proximate left-hand traffic rail of the block. The polarities of the local contacts change however in accord with the polarity of the rails of the block 15 20 served by the local signal station to which the electric conductors from said local contacts lead.

The vehicle is provided with traveling contacts 101, 102, which may be arranged in 25 duplicate at the respective sides of the track. They are arranged to coact with the local contacts. An electric translating device 103 is arranged to have electric connections with said traveling contacts for being brought 30 into accord with the electric translating device of the local signal station at the entrance of the block in advance of the position of the vehicle. This traveling electric translating device is exemplified as a polarized relay comprising polarized armatures 35 104, 105, and neutral armatures 106, 107, 108, and 109.

The direction of current in the polarized relay 103 is determined, during contact of 40 the traveling contacts with the local contacts, by the position of the pole-changer in the conductors leading from the local signal control battery 21 of the station with which the contacted local contacts connect, 45 the position of which pole-changer is controlled by the polarized relay 74 of said local signal station. The effect is to cause duplication on the vehicle of the local signal at the entrance to the advance station 50 in order that the driver of the vehicle may know the character of local signal he is approaching.

An electric conductor 110 is connected in 55 multiple by the terminals 111 with the traveling contacts 102 and with one of the terminals of the polarized relay 103. Electric conductors 112, 113, in which the armature 109 is interposed, connect the other terminal of the relay 103 with the traveling contacts 60 101, the latter connection being in multiple by the terminals 114. The polarized armatures 104, 105, are set up in accord with the polarization of the local signal control circuit of the local station of the block in advance upon contact of the traveling contacts 65

with the local contacts projected from said station.

I further provide a traveling maintaining circuit for maintaining the polarized armature in set-up relation when the traveling contacts have passed beyond the range of said local contacts. The maintaining circuit includes a battery 117, and a pole-changer 118 operated in manner to be herein-after described. The pole-changer is exemplified 70 as comprising contact-arms 119, 120, connected by an insulated bar 121, the arms arranged to make contact with the contacts 122, 123, 124. An electric conductor 125 connects with the normally positive traveling contacts 101 in multiple through the terminals 127, and with the contacts 122, 124 of the pole-changer 118. An electric conductor 128 connects with the normally negative traveling contacts 102 in multiple 80 through the terminals 129, and with the contact 123 of the pole-changer 118. An electric conductor 130 connects the positive pole of the battery 117 with the contact-arm 119 and an electric conductor 131 connects 90 the negative pole of the battery 117 with the contact-arm 120. The direction of current from the battery 117 to the traveling contacts is determined by the position of the pole-changer 118. These connections and 95 traveling battery 117 form a traveling partial maintaining circuit. The circuit is completed to the polarized relay 103 through the conductor 110, connecting with one terminal of said relay, and through the conductors 112, 113, and neutral armature 109, connecting with the other terminal of said relay.

The circuit is maintained in the direction determined by the local translating device 105 and pole-changing until the traveling contacts make contact with the next local contacts, which contacts cause the traveling contacts to bend away from the terminals 127, 129, for interrupting the circuit from 110 the traveling maintaining battery 117 and brings the traveling polarized relay 103 under sole influence of the local signal control battery 21 of the block in advance for again setting up the direction of current 115 through the traveling polarized relay 103, the traveling pole-changer 118 being correspondingly set up, so that when the traveling contacts 101, 102, leave the local contacts and again complete the circuit through 120 the traveling maintaining battery 117, the direction of current therefrom through the relay 103 will be the same as or in accord with the direction of flow therethrough from the local signal control battery 21 last 125 brought into action.

I shall now describe the traveling contacts exemplified, reference being had to Figs. 3, 4 and 5. The traveling contacts 101, 102, are similarly constructed so that description 130

of one will serve for both. The traveling contact 102 is a resilient electro-conductive bar, for instance, of steel, and depends from a suitable part of the traveling vehicle, as 5 from the bolster 136 of an engine. Resilient electro-conductive strips 137, 138, extend parallel to the bar 102. A brace 139 also depends from the bolster. The bar, strips and brace are securely clamped together and to 10 an angle-iron 140 by a clamp-bolt 141, insulating strips 142 insulating said parts from each other, an insulating sleeve 144 being about the bolt. The angle-iron is rigidly secured to the bolster. A bolt 145 is 15 securely held in the brace.

An insulating sleeve 146 surrounds the bolt and extends through clearance holes 147, 148, in the strip 138 and bar 102 and abuts against an insulating washer 149 at 20 one side of the strip 137, an insulating washer 150 being received about the bolt between the other side of the strip 137 and the head of the bolt, an insulating collar 151 being received about the bolt between said 25 washers in a hole in said strip 137. A spring 153 about the insulating sleeves 146 between the brace 139 and an insulating washer 154 at the strip 138 normally presses said strip toward the bar 102. Electric contact is normally had between the terminals 111, 129, 30 on the strips 138, 137, and said bar. When the bar or a suitable shoe thereon strikes a local contact, the bar will be bent away from the contact 129 for interrupting the 35 circuit of the traveling maintaining battery 117.

In order to prevent too violent contact between the traveling and local contacts, I prefer to incline the ends of the local contact rails, as shown at 155. I prefer also to 40 have the traveling contacts 101, 102, in duplicate, and the connections therefrom in multiple.

When the traveling maintaining circuit 45 is employed, the local signal control battery 21 of the block in advance and the traveling maintaining battery 117 will at times be momentarily in series upon initial contact of the traveling contacts 101, 102, with the 50 local contacts 90, 92, before the traveling contacts 101, 102, have been flexed away from the terminals 127, 129. This happens for instance when the traveling signal mechanism is set up as shown in Fig. 1, in which 55 the right-hand contacts 101, connect with the positive pole of the traveling battery 117 and the left-hand contacts 102 connect with the negative pole of said battery, and when they, in this condition, reach the local contacts projected from a station set up like the 60 station C', with the right-hand local contact connecting with the negative pole and the left-hand local contact connecting with the positive pole of the local battery 21 of station C'. This condition of the batteries 21

and 117 being in series, is only for an instant.

In order, however, to prevent the current from the battery 21 flowing through the battery 117, and causing a part of the current of the battery 21 to pass through the traveling electric translating device 103, I introduce electric resistance devices 157, 158, into the electric conductors between the traveling maintaining battery 117 and the 75 traveling contacts.

These traveling electric resistance devices will, however, during the closed condition of the traveling maintaining circuit during 80 travel of the vehicle, between the local contacts of adjacent blocks, permit sufficient flow of current from the battery 117 through the traveling electric translating device 103 to maintain the function of the latter, as said flow will be a regular flow, the resistance 85 functions of the resistances 157, 158, being effective during the electric series connection between the batteries 21 and 117.

Traveling signal devices are provided which under the influence of the traveling 90 electric translating device 103 are caused to duplicate the local signal of an advance block. These traveling signal devices are suitably operated. I have shown them operated by compressed fluid and controlled 95 by electric circuits. I provide electro-pneumatic valves 161, 162, 163, for the purpose. The electro-pneumatic valve 161 controls the white or clear, or proceed signal, exemplified as an electric lamp 164, the electro-pneumatic valve 162 controls the green or caution signal, exemplified as an electric lamp 165, and the electro-pneumatic valve 163 controls the red or stop signal, exemplified 100 as an electric lamp 166.

The electro-pneumatic valves respectively 105 comprise electro-magnets 167, 168, 169, and are arranged to feed cylinders 171, 172, 173, in which pistons 174, 175, 176, reciprocate, the pistons having rods 177, 178, 179, extending therefrom. Each of the electro-pneumatic valves, (see Figs. 1 and 2), comprises an inlet-valve *i*, arranged to be urged to seating position by a spring *k*; and an outlet-valve *l*, the inlet and outlet valves being connected by a stem *m*, and connecting with the armature *n* of the electro-magnet. A. passage *o* communicates with the cylinder. An inlet-port *p* and an outlet-port *q* 115 are provided.

The electro-pneumatic valves 161, 162, 163, are fed from a suitable source of compressed air, as from the usual compressed air reservoir 180 on the locomotive, by pipes 181, 182, 183, connecting said reservoir 125 with the inlet-ports of said respective electro-pneumatic valves. The amount of air required to operate the pistons through these valves is small and will not affect the air-brake system, especially if taken from 130

the reservoir, it being not desirable to affect the air-brake system when the valves 161, 162, are operated as they are respectively for clear and caution conditions of track, provision being however for bringing the braking system into action when valve 163 is operated.

I form connections whereby, when the electro-pneumatic valve 163 is operated, a 10 relief of pressure in the braking system is effected so as to cause an application of the brakes, this connection being exemplified as with the train-pipe 184, the connection being preferably made on the line leading to 15 the engineer's brake valve. I provide means whereby, when the inlet-valve *i* of the electro-pneumatic valve 163 is closed by the breaking of the circuit of its electro-magnet, the air from the train-pipe is vented, preferably to the atmosphere, in order to make 20 an emergency application of the brakes through the usual brake-system with which the train-pipe 184 connects. For this purpose a branch pipe 186 leads from the train-pipe and communicates with a valve-seat 187 25 normally closed by a valve 188 on the piston-rod 179.

The pressure of the air in the train pipe being normally on the piston 176, which is 30 of greater area than the area of the opening of the valve-seat 187, the valve 188 is normally closed. When however the exhaust-valve *l* opens to release the air in the cylinder 173, the valve 188 unseats, due to 35 recession of the piston, causing a sudden venting of the air in the pipe of the brake-system, and causing application of the brakes of the brake-system of the train, bringing the train to a stop with an emergency stop.

40 The pistons 174, 175, are normally retracted by springs *r*.

The traveling signals are controlled through a traveling source of electric power, represented as a traveling signal control 45 battery 191, from which electric conductors connect with the electro-magnets 167, 168, 169, for controlling the same, and to the electric lamps for lighting the same.

The traveling signal mechanism is shown 50 set up in Figs. 1 and 2, for showing white or a clear block ahead. An electric conductor 192 connects with one pole of the traveling battery 191 through the conductor 131, and through the neutral armature 107 with 55 an electric conductor 193, through the polarized armature 105, in contact with the terminal 194 of an electric conductor 195 connecting with one terminal of the electro-magnet or translating device 167. An electric conductor 196 connects with the other 60 terminal of the electro-magnet 167 and connects with the terminal 197 with which electric connection is made by an electric conductor 198 through the polarized armature 65 104, the electric conductor 198 connecting

with an electric conductor 199 through the neutral armature 106 and through an electric conductor 200 with the other pole of the battery 191.

The neutral armatures 106, 107, being 70 drawn up, and the polarized armatures 104, 105, being swung to cause contact with the terminals 197, 194, circuit from the battery 191 is had with the electro-magnet 167, for opening the electro-pneumatic valve 161 and 75 pushing the piston 174 forward, whereby the pole-changer 118 is swung, the arm 119 thereof being articulated at 203 with the piston-rod 177. Furthermore an electric switch 204, articulated at 205 with the 80 piston-rod 177 makes contact with the terminal 206, thereby closing the light-circuit for the white light 164 from the battery 191, and causing lighting of said light. This light-circuit comprises the electric conductor 131, an electric conductor 207 connecting therewith and with one terminal of the light 164, an electric conductor 208 connecting the other terminal of said light with said switch 204, the terminal 206 being 90 connected with an electric conductor 209 connecting with the conductor 200.

If now the vehicle proceeds in the direction of the arrow *g* until the traveling contacts make contact with the local contacts 95 projected from station B', the signal of which is also in white or clear position, indicating proceed condition of the block, the circuit with the traveling maintaining battery 117 will be momentarily interrupted 100 by the recession of the traveling contacts 101, 102, from the terminals 127, 129, but no change in relation of the traveling signals will take place as they are already in 105 accord with the signal at the station B' at the entrance to block B.

The vehicle proceeding in block B will cause contact between the traveling contacts 101, 102, and the local contacts 90, 92, 110 projected from the station C' at the entrance to block C. The block C has been temporarily changed into a caution block by the danger condition of block D, as hereinbefore explained, the polarities of its tracks having been reversed, and the polarities of said local contacts projected rearwardly from the station at its entrance having also been reversed in manner hereinbefore explained and, as indicated by the plus and minus signs in Fig. 1. 115

The contact of the traveling contacts with the local contacts will cause recession of the traveling contacts from the terminals 127, 129, thereby interrupting the circuit in which the traveling maintaining battery 117 is located and completing the circuit between the local signal control battery 21 of station C' with the traveling electric translating device 103, as hereinbefore explained. The 125 result of the formation of this current with 130

the local signal control battery 21 of station C' is to instantly change the direction of flow of current through the traveling electric translating device 103 and change the 5 polarity thereof, for the reason that the polarities of the local contacts projected from the station C' are the reverse of the preceding setting up of the traveling signal devices.

10 The polarity of the traveling electric translating device 103 being changed, its polarized armature or armatures will instantly correspondingly change and swing for causing contact of the polarized armatures 104, 105, respectively with the terminals 211, 212. This change of contact will 15 interrupt the current from the battery 191 through the electro-magnet 167 and simultaneously complete the circuit through the 20 electro-magnet 168, an electric conductor 213 connecting the terminal 211 with one of the terminals of the electro-magnet 168 and an electric conductor 214 connecting the terminal 212 with the other terminal of the 25 electro-magnet 168.

The interrupting of the current through the electro-magnet 167 will cause closing of the inlet-valve *i* and opening of the outlet-valve *l* of electro-pneumatic valve 161 for 30 opening the cylinder 171 for permitting retraction of the piston 174 and the discharge of the compressed air from the cylinder 171, the discharge in this instance taking place through the signal whistle 215, the highly 35 compressed air passing through the whistle, giving a short sharp blast to notify the engineer that the vehicle is about to leave a clear or proceed track and is approaching a caution or danger track. The retraction of 40 the piston 174 will also swing the switch 204 for shutting off the clear or white light 164, the green light 165 being instantly lighted. It may be here stated that in railway traffic practice absence of a signal indicates danger, and causes the driver to stop 45 the vehicle.

As soon as the electro-magnet 168 has been energized as aforesaid, the outlet valve *l* of the electro-pneumatic valve 162 will 50 close and its inlet valve *i* open for causing movement of the piston 175 of the cylinder 172. The piston-rod 178 of the piston 175 is articulated at 218 with a switch 219 arranged to make contact with the terminal 220 extending 55 from the electric conductor 209 for causing lighting of the green light 165, which has an electric conductor 221 connecting with the switch 219 and with one of the terminals of the light 165, and an electric conductor 222 connecting the other of the terminals of said light with the electric conductor 181, the electric conductors 209 and 181 extending to the battery 191, as hereinbefore explained.

65 Assuming now that the vehicle proceeds

under caution into block C, it will eventually reach the local contacts projected from the station D' located at the entrance of block D, block D being a danger block caused for instance by the presence therein of a vehicle, 70 indicated by the axle and wheels Z. The presence of this vehicle Z in block D has caused short circuiting across the local battery 61 of the station at the entrance of the next block in advance, thereby taking the 75 current of said battery from the local electric translating device 74 at station D', causing dropping of the neutral armature 48 and the breaking of the circuit energizing the electro-pneumatic valves 43, 44, and closing 80 of the electro-pneumatic valves 23, 24, at station D', for causing the signal or semaphore arm at said station to drop to horizontal position and indicate a red light, which action also opens the circuit breaker 85 51 for breaking the normally interrupted circuit of local signal control battery 21 of station D' with the local contacts connected therewith at the side of the rails in block C.

When now the traveling contacts make 90 contact with said last-named local contacts for moving said traveling contacts away from the terminals 127, 129, connecting with the traveling maintaining battery 117, the circuit through the traveling polarized relay 95 103 will be interrupted and said relay de-energized whereby all the neutral armatures 106, 107, 108 and 109 will drop and all circuits through the traveling battery 191 will be broken, current being taken from all of 100 the electro-magnets 167, 168, 169, and all of the pistons 174, 175, 176, not already in retracted position will move to retracted positions for causing extinction of the lights 164, 165, and further causing the closing of the 105 circuit of the red light 166 with the traveling battery 191. This action also causes the application of the brakes of the train braking system through the opening of the valve 188, as hereinbefore explained.

110 The red light 166 has one of its terminals connected by an electric conductor 225 with the electric conductor 181, the other of the terminals of said lamp being connected by an electric conductor 226, which connects with a switch 227 articulated at 228 with the piston-rod 179, and arranged to contact a terminal 229 connected by an electric conductor 230 with the electric conductor 209 and thence to the battery 191.

120 The emergency application described will bring the train to a quick but easy stop, as it does not shut off the steam from the engine, this shutting off of steam being inadvisable, as the shutting off of the steam 125 upon application of an emergency in the braking system causes jarring of the train. It is contemplated that the steam in my improved system will be shut off by the engineer, but whether shut off or not the 130

train comes quickly to a dead and easy stop, prior to the entrance of the train into the danger block, as the changing of the traveling signal mechanism from green or caution to red or stop condition takes place at the local contacts which are sufficiently in rear of the block controlled by the same to cause the stoppage of the train prior to entrance of the train into the danger block.

10 The traveling signal mechanism having made a red or danger indication, and in the present exemplification having made an emergency application of the brakes, it is beyond the power of the driver of the vehicle to again cause the vehicle to proceed. It is desirable, however, to place the vehicle again under the control of the driver, but to so arrange the re-control device as to cause a lapse of time between the red or danger indication and the re-control of the travel of the vehicle, in order to enable the driver to collect his thoughts and to compel attention to what he is about to do.

I therefore provide a re-control button 236 placed at a position away from the usual position of the driver of the vehicle, as at the opposite side of the cab, or at some point compelling the driver to move from his position in order to reach the same.

15 I connect the button with connected switches 237, 238, by means of an insulated rod 239, the switches and button being normally retracted by a spring 240. An electric conductor 241 connects the switch 237 with the electric conductor 110 connecting with one terminal of the traveling polarized relay 103. An electric conductor 242 connects the terminal 243 for switch 247 with the electric conductor 128 connecting 20 with the terminal 123 of the pole-changer 118. An electric conductor 245 connects the switch 238 with the electric conductor 112 connecting with the other terminal of the traveling polarized relay 103. An electric conductor 246 connects with the terminal 247 of switch 238 and with the electric conductor 125, connecting with the terminal 124 of the traveling pole-changer 118.

25 When now the re-control button 236 is pressed, the switches 237, 238, make contact respectively with the terminals 243, 247, establishing the circuit from the traveling maintaining battery 117 through the electric conductor 131, the arm 120 of the traveling pole-changer 118 to the terminal 124, (it being understood that the pole-changer 118 is reversed from the position shown in Figs. 1 and 2), thence through the electric conductor 125, the electric conductor 246, the terminal 247, switch 238, and electric conductors 245 and 112 to one of the terminals of the traveling polarized relay 103, through the polarized relay to the other terminal thereof, the electric conductors 110 and 241, to the switch 237 and terminal 243,

electric conductor 242, terminal 123, traveling pole-changer arm 119, and electric conductor 130 back to the traveling maintaining battery.

This circuit will energize the traveling 70 polarized relay 103 and cause attraction of the neutral armatures 106, 107, 108, and 109, for closing the gaps established thereby. The traveling pole-changer 118 will be in green position and thereby establish current 75 from the traveling battery 191 with the electro-magnet 168 through the position of the polarized armatures 104, 105, causing contact with the terminals 211, 212.

The drawing up of the neutral armatures 80 by the reestablishing of the circuit through the traveling battery 117 and the traveling polarized relay 103, will also again cause energizing of the electro-magnet 169 and the opening of communication through the 85 electro-pneumatic valve 163 between the reservoir 181 and the cylinder 173 of the red or danger signal device. The pressure from the auxiliary reservoir upon the piston 176 will close the valve 188 in the train-line, 90 permitting the engineer to again pump up the train-line and remove application of the brakes.

This again places the train or vehicle under the control of the driver, by resetting 95 up the traveling signal devices, with the traveling signal mechanism in green or caution condition for permitting permissive movement of the train or vehicle under the control of the driver.

Having thus fully described my invention, what I claim as new and desire to secure by Letters Patent, is:

1. In a signal system for railways, the combination of a track divided into blocks, a local station at a block, means at said local station embodying an automatic pole-changer, a source of electric energy, said pole-changer arranged for reverse connections with the poles of said source of electric energy, and local contacts having electric connections with said pole-changer for forming a local partial circuit, the polarities of said local contacts being determined by said pole-changer, a traveling partial circuit, a 105 traveling polarized relay served thereby, said traveling partial circuit embodying traveling contacts arranged for contact with said local contacts for completing said partial circuits and arranging the polarity of said polarized relay in accord with the arrangement of said automatic pole-changer; a traveling partial circuit comprising a source of electric energy, and electric means connecting with said last-named traveling partial circuit for completing the circuit of said traveling source of electric energy with said traveling polarized relay for maintaining the polarity of said polarized relay.

2. In a signal system for railways, the 120

combination of a track divided into blocks; a local source of electric energy, a local contact, and means between said local source of electric energy and local contact for changing the electric value of said local contact at said respective blocks, a traveling partial circuit embodying a translating device, a traveling contact therefor arranged for making contact at intervals with said respective local contacts, a traveling partial circuit embodying a traveling source of electric energy, means between said traveling contact and traveling source of electric energy for changing the electric value of said traveling contact, and means whereby said local partial circuit comprising said local source of electric energy at said respective blocks and said traveling partial circuit comprising said traveling source of electric energy are selectively completed through said traveling partial circuit comprising said translating device, for setting up said traveling translating device in accord with the electric value of said respective local contacts upon contact of said traveling contact with said respective local contacts.

3. In a signal system for railways, the combination of a track divided into blocks; a local source of electric energy, a local contact, and means between said local source of electric energy and local contact for changing the electric value of said local contact, forming a local partial circuit at said respective blocks, a traveling partial circuit embodying a traveling translating device and a traveling contact therefor arranged for making contact at intervals with said respective local contacts, forming a traveling partial circuit, a second traveling partial circuit including a traveling source of electric energy, traveling signaling means, and electric controlling means therefor controlled by said translating device and embodying means for changing the electric value of said traveling contact, arranged whereby said local partial circuit at said respective blocks comprising said source of electric energy and said traveling partial circuit comprising said traveling source of electric energy are selectively completed through said traveling partial circuit comprising said translating device, for setting up said traveling translating device in accord with the electric value of said respective local contacts upon contact of said traveling contact with said respective local contacts, and for maintaining said set-up relation of said traveling translating device during intervals between contacts of said traveling contact with said respective local contacts.

4. In a signal system for railways, the com-

bination of a track divided into blocks; a local source of electric energy, a local contact, and means between said local source of electric energy and local contact for changing electric value of said local contact, forming a local partial circuit at said respective blocks, a traveling partial circuit comprising a traveling translating device, a traveling partial circuit comprising a traveling source of electric energy, and a traveling contact therefor arranged for making contact at intervals with said respective local contacts; traveling signaling means, and electric controlling means therefor embodying means for changing the electric value of said electric traveling contact in accord with said electric value of said respective local contacts, said controlling means controlled by said traveling translating device, said traveling signaling means including train controlling means, and arranged whereby said local partial circuit at said respective blocks comprising said source of electric energy and said traveling partial circuit comprising said traveling source of electric energy are selectively completed through said traveling partial circuit comprising said translating device, for setting up said traveling translating device in accord with the electric value of said respective local contacts upon contact of said traveling contact with said respective local contacts, and for maintaining said set-up relation of said traveling translating device during intervals between contacts of said traveling contact with said respective local contacts.

5. In a signaling system for railways, the combination of a track divided into blocks, local stations respectively at the entrance to said blocks, said local stations comprising signaling means for clear condition, caution condition and danger condition of blocks arranged whereby when said signaling means of a block in advance indicates danger condition of said block the signal for a block in rear will show caution condition, a traveling signaling mechanism comprising signals for clear condition, caution condition and danger condition; partial circuits at said respective local signal stations comprising a source of electric energy and a local contact in a block in rear, a traveling partial circuit for controlling said traveling signals and comprising a traveling contact arranged for contact with said local contacts, means whereby when contact between said traveling contact and a local contact is made the traveling signaling means is set up in accord with the local signaling means, and a traveling maintaining partial circuit arranged for connection with said partial traveling signal control circuit for maintaining said traveling signaling means in set-up relation.

6. In a signaling system for railways, the combination of a track divided into blocks,

local stations respectively at the entrance to said blocks, said local stations comprising signaling means for clear condition, caution condition and danger condition of blocks arranged whereby when said signaling means of a block in advance indicates danger condition of said block the signal for a block in rear will change to caution condition of said block in rear, a traveling signaling mechanism comprising signals for clear condition, caution condition and danger condition, partial circuits at said respective local signal stations comprising local contacts in blocks in rear, a traveling partial circuit for controlling said traveling signals and comprising traveling contacts arranged for contact with said local contacts, means whereby when contact between said traveling contacts and local contacts is made the traveling signaling means is set up in accord with the local signaling means of the block in advance, a traveling maintaining partial circuit arranged for connecting with said traveling partial signal control circuit for maintaining said traveling signaling means in set-up relation, said traveling signal control means arranged for interruption of said traveling partial signaling circuit upon arrangement of said traveling signals for danger condition, and means under the control of the operator for reestablishing said traveling signaling circuit.

7. In a signal system for railways, the combination with a track divided into blocks, of a plurality of local signals, a local signal control circuit comprising a plurality of legs for selectively setting up said plurality of signals, a track circuit extending from a block in advance embodying a translating device for setting up the flow of electricity selectively through said legs of said local signal control circuit, local contacts in rear of and having electric connection with said local signal control circuit, a plurality of traveling signals, a traveling signal control circuit therefor embodying a plurality of legs, a traveling partial circuit embodying a translating device for controlling the flow of electricity selectively through said respective legs, traveling contacts arranged for contacting said local contacts and thereby setting up said traveling signal control circuit in accord with the setting up of said local signal control circuit, and a traveling maintaining partial circuit arranged for completing said traveling partial circuit in which said traveling translating device is located.

8. In a signal system for railways, the combination of a vehicle, a traveling electric translating device thereon, local signals, a local partial setting-up circuit controlled thereby, a plurality of traveling signals adjacent to the driver's position on said vehicle, partial electric circuits controlling said

signals respectively, a traveling source of electric energy, controlled means under the control of said translating device connecting any of said partial circuits with said traveling source of electric energy in accord with the setting-up control of said local partial setting-up circuit, a traveling partial maintaining circuit arranged for selective connection with said translating device, said traveling partial maintaining circuit including a part of said controlled means, and means on said vehicle under the control of the driver of the vehicle distanced from said driver's position for re-control of said translating device by connection with said traveling partial maintaining circuit.

9. In a signal system for railways, the combination of traveling electro-pneumatic valves comprising electro-magnets for controlling said valves, said electro-pneumatic valves including valves for clear condition, caution condition and danger condition of track ahead, partial electric circuits in which said electro-magnets for clear condition and for caution condition of track ahead are respectively included, a traveling source of electric energy, a traveling translating device, a partial traveling circuit in which said translating device is included, a local partial circuit controlling said translating device, and movable connecting means under the control of said translating device for electrically connecting either of said first-named partial circuits controlling said electro-pneumatic valves for clear condition and for caution condition of track ahead with said traveling source of electric energy, said traveling source of electric energy being normally in circuit with said electro-magnet of said electro-pneumatic valve for danger condition of track ahead, and said translating device arranged for being deenergized upon danger condition of track ahead for release of all said electro-magnets.

10. In a signal system for railways, the combination of traveling electro-pneumatic valves comprising electro-magnets for controlling said valves, signal actuating mechanism comprising a compressed fluid chamber for each of said valves, partial electric circuits in which said magnets are included, a traveling source of electric energy, a traveling translating device, a partial traveling circuit in which said translating device is included, a local partial circuit controlling said translating device, movable connecting means under the control of said translating device for electrically connecting either of said first-named partial circuits with said traveling source of electric energy, and a whistle connected with said compressed fluid chamber of one of said signal actuating mechanisms, whereby upon actuation of said last-named actu-

ating mechanism said compressed fluid of said chamber is released through said whistle for causing blowing of said whistle.

11. In a signal system for railways, the combination of traveling electro-pneumatic valves respectively for clear condition, caution condition and danger condition of track ahead, an electric translating control device for each of said valves, a partial electric circuit for each of said electric translating control devices, a traveling electric translating device, a traveling source of electric energy for said respective traveling translating control devices, and electrically controlled means for selectively causing electric connection between said traveling source of electric energy and either one of said electro-pneumatic valves controlling clear condition and caution condition of track ahead and normally causing connection between said traveling source of electric energy and said electro-pneumatic valve for danger condition of track ahead and comprising means whereby said partial circuits are interrupted from said traveling source of electric energy.
12. In a signal system for railways, the combination of traveling electro-pneumatic valves respectively for clear condition, caution condition and danger condition of track ahead, an electric translating control device for each of said valves, a partial electric circuit for each of said electric translating control devices, a traveling electric translating device, a traveling source of electric energy for said respective traveling translating control devices, electrically controlled means for selectively causing electric connection between said traveling source of electric energy and either one of said electro-pneumatic valves controlling clear condition and caution condition of track ahead and normally causing connection between said traveling source of electric energy and said electro-pneumatic valve for danger condition of track ahead and comprising means whereby said partial circuits are interrupted from said traveling source of electric energy, and a traveling partial maintaining circuit normally connected with said traveling translating device.

13. In a signal system for railways, the combination of a track divided into blocks, local signals at the entrance of blocks comprising signals for clear condition, caution condition and danger condition of track ahead, a local pole-changer controlled by the state of said signals, a partial circuit projected in rear of said local signals and controlled in polarity by said pole-changer, a traveling polarized relay, a traveling partial circuit therefor arranged for connection with said partial circuit projected in rear for causing accord between said polarized relay and said pole-changer, a traveling

source of electric energy, a plurality of electro-pneumatic valves respectively for clear condition, caution condition and danger condition of track ahead, signals controlled by said respective valves, electro-magnets for controlling the same, a partial circuit for each of said electro-magnets for clear condition and caution condition of track ahead, a traveling source of electric energy, a polarized armature controlled by said traveling polarized relay for causing selective connection between said traveling source of electric energy and said last two-named electro-pneumatic valves, and a neutral relay or relays controlled by said traveling relay for controlling electrical connection between said traveling source of electric energy and said electro-pneumatic valve for danger condition of track ahead.

14. In a signal system for railways, the combination of a track divided into blocks, local signals at the entrance of blocks comprising signals for clear condition, caution condition and danger condition of track ahead, a local pole-changer controlled by the state of said signals, a partial circuit projected in rear of said local signals and controlled by the polarity of said pole-changer, a traveling polarized relay, a traveling partial circuit therefor arranged for connection with said partial circuit projected in rear for causing accord between said polarized relay and said pole-changer, a traveling source of electric energy, a plurality of electro-pneumatic valves respectively for clear condition, caution condition and danger condition of track ahead, signals controlled by said respective valves, electro-magnets for said respective valves for controlling the same, a partial circuit for each of said electro-magnets for clear condition and caution condition of track ahead, a traveling source of electric energy, a polarized armature controlled by said traveling polarized relay for causing selective connection between said traveling source of electric energy and said last two-named electro-pneumatic valves, a neutral relay or relays controlled by said traveling relay for controlling electrical connection between said traveling source of electric energy and said electro-pneumatic valve for danger condition of track ahead and comprising means whereby said partial circuits are interrupted from said traveling source of electric energy, and a traveling partial maintaining circuit normally connected with said traveling translating device.
15. In a signal system for railways, the combination of a track divided into blocks, local signals at the entrance of blocks comprising signals for clear condition, caution condition and danger condition of track ahead, a local pole-changer controlled by the state of said signals, a partial circuit projected in rear of said local signals and con-

- trolled in polarity by said pole-changer, a traveling polarized relay, a traveling partial circuit therefor arranged for connection with said partial circuit projected in rear for causing accord between said polarized relay and said pole-changer, a traveling source of electric energy, a plurality of electro-pneumatic valves respectively for clear condition, caution condition and danger condition of track ahead, signals controlled by said respective valves, electro-magnets for said respective valves for controlling the same, a partial circuit for each of said electro-magnets for clear condition and caution condition of track ahead, a traveling source of electric energy, a polarized armature controlled by said traveling polarized relay for causing selective connection between said traveling source of electric energy and said last two-named electro-pneumatic valves, a neutral relay or relays controlled by said traveling relay for controlling electrical connection between said traveling source of electric energy and said electro-pneumatic valve for danger condition of track ahead, and a traveling partial maintaining circuit including a traveling source of electric energy arranged for connection with and interruption from said partial circuit including said polarized relay.
16. In a signal system for railways, the combination of a track divided into blocks, local signals at the entrance of blocks comprising signals for clear condition, caution condition and danger condition of track ahead, a local pole-changer controlled by the state of said signals, a partial circuit projected in rear of said local signals and controlled in polarity by said pole-changer, a traveling polarized relay, a traveling partial circuit therefor arranged for connection with said partial circuit projected in rear for causing accord between said polarized relay and said pole-changer, a traveling source of electric energy, a plurality of electro-pneumatic valves respectively for clear condition, caution condition and danger condition of track ahead, signals controlled by said respective valves, electro-magnets for said respective valves for controlling the same, a partial circuit for each of said electro-magnets for clear condition and caution condition of track ahead, a traveling source of electric energy, a polarized armature controlled by said traveling polarized relay for causing selective connection between said traveling source of electric energy and said last two-named electro-pneumatic valves, a neutral relay or relays controlled by said traveling relay for controlling electrical connection between said traveling source of electric energy and said electro-pneumatic valve for danger condition of track ahead, a traveling partial maintaining circuit including a traveling source of electric energy ar-
- ranged for connection with and interruption from said partial circuit including said polarized relay, and a pole-changer under control of one of said traveling signals for changing the direction of flow of current from said traveling source of electric energy through said polarized relay in accord with the positions of said signals.
17. In a signal system for railways, the combination of a track divided into blocks, a local source of electric energy, local contacts projected in rear of a given block, a pole-changer between said local source of electric energy and local contacts for changing the polarities of said local contacts, a traveling source of electric energy, traveling contacts electrically connected with said traveling source of electric energy, said electrical connections including an electric resistance or resistances, and a translating device arranged for connection with either or both of said partial circuits including said sources of electric energy, said resistance or resistances arranged for influencing flow from said local electric source of energy to said translating device when said batteries are in series by contact of said traveling contacts with said local contacts.
18. In a signal system for railways, the combination of a traveling electro-pneumatic valve for clear condition of track ahead, a traveling electro-pneumatic valve for caution condition of track ahead, traveling signal operating means connecting with said respective electro-pneumatic valves including compressed air mechanism comprising a chamber, a traveling compressed air reservoir for feeding said electro-pneumatic valves, a traveling source of electric energy having electric connection with said electro-pneumatic valves for controlling the same, a traveling polarized relay for controlling said electrical connections to either of said electro-pneumatic valves and for controlling a traveling pole-changer for controlling the direction of flow through said polarized relay, and a traveling partial maintaining circuit for said polarized relay which includes said pole-changer.
19. In a signal system for railways, the combination of a traveling electro-pneumatic valve for clear condition of track ahead, a traveling electro-pneumatic valve for caution condition of track ahead, a traveling electro-pneumatic valve for danger condition of track ahead, traveling signal operating means connecting with said respective electro-pneumatic valves including compressed air mechanism comprising a chamber, a traveling compressed air reservoir for feeding said electro-pneumatic valves, a traveling source of electric energy having electric connections with said electro-pneumatic valves for controlling the same, a traveling polarized relay for con-

trolling said electrical connections to either of said first two named electro-pneumatic valves and for controlling a pole-changer for controlling the direction of flow through said polarized relay, said traveling polarized relay controlling the making or breaking of said electrical connection with said electro-pneumatic valve for danger condition of track ahead, and a traveling partial main-

taining circuit for said polarized relay which 10 includes said pole-changer.

In testimony whereof, I have hereunto signed my name in the presence of two subscribing witnesses.

CLINTON F. SHADLE.
